UNITED STATES PATENT OFFICE.

JOHN WATSON, OF PASSAIC, NEW JERSEY, ASSIGNOR TO MERGENTHALER LINOTYPE COMPANY, A CORPORATION OF NEW YORK.

TYPOGRAPHICAL MACHINE.

1,099,478.

Specification of Letters Patent.

Patented June 9, 1914.

Application filed December 12, 1912. Serial No. 736,267.

To all whom it may concern:

Be it known, that I, JOHN WATSON, a citizen of the United States, and a resident of Passaic, county of Passaic, and State of New Jersey, have invented a new and useful Improvement in Typographical Machines, of which the following is a specification.

My invention relates to typographical machines, such as linotype machines of the general organization represented in Letters Patent of the United States to O. Mergenthaler, No. 436,532, wherein circulating matrices are released from a magazine in the order in which their characters are to appear in print and then assembled in line, the composed line transferred to the face of a slotted mold, the mold filled with molten metal to form a slug or linotype against the matrices which produce the type characters thereon, and the matrices thereafter returned through a distributing mechanism to the magazine from which they started. In such machines the matrices are carried to and from the mold by a device commonly known as the "first elevator" which moves up and down in a vertical guideway in front of the mold. After this elevator has been lowered to its proper casting position, the mold is moved forward against the line of matrices, the line justified, and the casting proceeded with. As is well known in this class of machines, before the casting takes place, the elevator is urged upward to a slight extent in order to effect the alinement of the matrix characters with the mold slot, this alinement usually being secured by the engagement of the lower ears of the matrices with a grooved plate, generally known as the "keeper plate", carried by the mold. In practice it sometimes happens that the parts will be presented in such relation that the matrix ears will not enter properly into the alining grooves of the keeper plate, which will result in the imperfect alinement of the matrix characters with the mold slot. Thus, for example, it may occur that the mold wheel or carrier will be moved beyond its normal position so that when the mold is advanced against the matrices, the alining groove will occupy an inclined position with relation to the matrix ears. Or the imperfect alinement may result from inaccurate workmanship, or from the expansion and contraction of the mold due to the varying temperatures to which it is subjected.

It is the principal object of my invention to overcome this objection, and to this end I provide the first elevator with a matrix supporting head capable of a free rocking movement thereon about an axis extending transversely of the mold, the supporting head thus moving vertically relatively to the first elevator and in a plane parallel or substantially so with the face of the mold. As a result of this construction the supporting head may readily adjust itself to the varying positions of the mold and thus insure proper alinement of the parts.

While in the accompanying drawing I have shown my invention as applied to the particular type of machine referred to, it is to be understood that it may be applied as well to other types of typographical machines and, further, that it may embody other forms and details without departing from the spirit of the invention. Generally speaking, I desire it to be distinctly understood that I do not limit myself to any specific embodiment or adaptation of the invention except in so far as such limitations are specified in the claims.

Referring to the drawings: Figure 1 is a rear perspective view of the casting mechanism of a linotype machine having my invention applied thereto, showing a "quad-block" supported by the elevator in front of the mold, the mold being shown in section and its supporting wheel or carrier being shown in dotted lines; Fig. 2 is a section taken on the line 2-2 of Fig. 1; Fig. 3 is an end view of the elevator head showing a different mode of attachment of the "quad-block"; Fig. 4 is a similar view showing the form of elevator head employed for supporting a line of matrices; and Fig. 5 is a face view of the parts shown in Fig. 4.

As usual, the mold A is carried by the rotatable mold wheel B and is provided with the horizontal mold slot a in which the slug is cast. To the mold there is rigidly secured to the so-called keeper plate C having on its face one or more horizontal grooves c, c¹, to engage the lower ears of the matrices and effect their accurate alinement with the mold slot a. The matrices are presented to the mold by the first elevator D which slides up and down in a vertical guideway (not shown) in front of the mold, and which elevator comprises a head or support for the matrices. During the downward movement

of the first elevator, the mold stands in a retracted position in order to permit the projecting ears of the matrices to move past the same. When, however, the elevator has reached its proper casting position, 5 the mold advances facewise against the line of matrices and engages one of the grooves c, c^1 , in the keeper plate C, with the matrix ears, after which the elevator is urged 10 slightly upward to effect the accurate alignment of the matrices. So far as described, the parts are or may be substantially the same as those disclosed in the Letters Patent referred to or as employed in the commercial linotype machine.

15 As previously pointed out, it sometimes happens that when the mold A is advanced facewise against the line of matrices, the matrix ears will not be properly engaged 20 with the grooves in the keeper plate C. This may result from the mold being presented out of proper alining position with 25 relation to the matrices, or from other causes; and if in these circumstances the matrix supporting head is rigidly connected 30 with the first elevator as heretofore, there will be a failure to secure the final alinement of the parts. To obviate this objection I mount the matrix supporting head upon the first elevator so that it may have a 35 free rocking movement thereon transverse of the mold.

Referring to Figs. 1 and 2, the matrix supporting head is in the form of a plate E 35 pivotally connected to the first elevator D by a pivoting screw F. In said figures, the plate E is shown as giving support to a "quad-block" G provided at its opposite ends with projecting lips g to engage in one 40 of the alining grooves of the keeper plate C. As a convenient means for supporting the block G upon the plate E, I have shown these parts connected by a dovetail, which 45 will permit the ready removal of the block G when desired. In addition it will be noted that by means of this mode of connection the block G is supported wholly at its rear, thereby leaving its front or operative side wholly exposed in order that it 50 may coöperate freely with the mold, and so that when the parts are in their casting position they will be firmly held therein. In Figs. 3 and 4 a substantially similar means of support is disclosed. In this instance, the 55 plate E is provided with a projecting tongue H of T-shape in cross-section and fitting into a correspondingly shaped groove in the face of the block G. This tongue is preferably made of a vertical width equal to or less 60 than the distance between the upper and lower ears of a matrix, in order that in the use of matrices it may be employed as one of the supporting ledges therefor. Thus in Fig. 4 it is shown as supporting one side of 65 a line of matrices X, the other side of

which is supported upon a ledge J extending inwardly from a bracket I secured to the face of the plate E. This bracket I is detachably secured to the plate by bolts K so that it may be removed therefrom when 70 desired to permit the use of the quad-block shown.

From the construction described, it will be noted that even though the mold A be not presented in the exact position required, 75 the matrix supporting head by reason of its pivotal connection may readily adjust itself relatively thereto and thus secure proper alinement. It will also be noted that the rocking movement of the elevator head may 80 be availed of for other purposes than those described, as, for instance, to effect its alinement with other parts of the machine. These and other uses will readily suggest themselves to those skilled in the art and 85 still be comprised within the scope of the invention.

Having thus described my invention, its construction and mode of operation, what I claim and desire to secure by Letters Patent 90 of the United States is, as follows:

1. In a typographical machine comprising casting mechanism, the combination of a slotted mold and a matrix support pivotally mounted so as to rock about an axis extending 95 transversely of the mold.

2. In a typographical casting machine, the combination of a matrix support, and a slotted mold provided with alining means to engage the matrices carried by the support, the said support being mounted to be rocked relatively to the mold in a plane parallel or substantially so with the face thereof by the engagement of the matrices with said alining means; whereby the accurate alinement of the matrices with the mold slot will 100 be secured.

3. In a typographical casting machine, the combination of a matrix support, and a mold slotted horizontally and provided with alining means to engage the matrices carried by the support, said support being mounted to be rocked in a vertical plane relatively to the mold by the engagement of the matrices with said alining means, in order to insure 110 the horizontal alinement of the matrix characters with the mold slot.

4. In a linotype machine, the vertically movable first elevator provided with a matrix supporting head pivotally mounted 120 thereon to rock about a horizontal fore and aft axis in a vertical plane relative thereto.

5. In a typographical machine, the combination of a slotted mold provided with alining means, and a coöperating matrix element supported in front of the mold in position to engage said alining means, the said element being movably mounted so as to be rocked relatively to the mold by its engagement 125 with the alining means.

6. In a typographical machine comprising casting mechanism, the combination of the mold provided with matrix alining means and the first elevator to present the matrices thereto and movable to effect their alinement therewith, the said elevator being provided with a matrix supporting head adapted to be moved relatively thereto by the engagement of the matrices with the said 10 alining means during the alining movement of the elevator.

7. In a typographical machine comprising casting mechanism, the combination of the mold provided with matrix alining means 15 and the first elevator for presenting the mat-

rices thereto and movable to effect their alinement therewith, the said elevator being provided with a matrix supporting head mounted to rock freely thereon and the said rocking movement being effected by the engagement of the matrices with the said alining means during the alining movement of the elevator. 20

In testimony whereof I hereunto set my hand this seventh day of December, 1912, in 25 the presence of two attesting witnesses.

JOHN WATSON.
